[57] CLAIM

The ornamental design for a combined bottle and cap, substantially as shown and described.

DESCRIPTION

FIG. 1 is a front elevational view of a combined bottle and cap showing our new design, the rear elevational view being substantially a mirror image thereof;

FIG. 2 is a side elevational view thereof, the opposite side being substantially a mirror image thereof;

FIG. 3 is a bottom plan view thereof; and

FIG. 4 is a top plan view thereof.
